GUARD RAIL

Alan E. Brickman and George A. Gleason,
Worcester, Mass., assignors to The Ameri-
can Steel and Wire Company of New Jersey,
a corporation of New Jersey

Application August 14, 1934, Serial No. 739,826

3 Claims. (Cl. 256—13.1)

This invention relates to guard rails of the type using flat metal strips, one of the objects being to properly tension the strips regardless of the expansive and contractive effects caused by temperature changes. Another object is to reduce the tendency that a colliding vehicle has to climb over the strips. Other objects may be inferred.

Referring to the accompanying drawing:

10 Figure 1 is an elevation of an example of the invention.

Figure 2 is a plan of Figure 1.

Figure 3 is an elevation of another example of the invention.

15 Figure 4 is a cross-section taken from the line IV—IV in Figure 3.

Figure 5 is a plan of Figure 4.

More specifically, Figures 1 and 2 show a guard rail including a flat spring metal member 1 that is looped at both sides of its center as at 1^a, so as to bring its end portions 1^b together, its ends being cut and formed to provide interfitting and mutually registering elongated loops 1^c. The flat metal strips 2 are arranged with their ends 25 adjacently abutting and fixed to the end portions 1^b whereby they are urged together by the elasticity of the member 1. A pin 3 is arranged through the elongated loops 1^c so that a construction somewhat like a loosely fitting piano hinge results.

30 The spring member 1 constantly maintains the proper tension in the strips 2. If a colliding vehicle strikes one of the strips 2 so that sufficient force is transmitted to the member 1 to cause it to spread excessively, the looped ends 1^c engage the pin 3 and prevent the connection between the strips 2 from being broken, or introducing too much slack.

35 In Figures 3 through 5 the member 1 is mounted through a spring metal bar 4 by one of the guard rail posts 5 in an upright position by its upper part so that its lower part may swing towards the post.

The post 5 is a steel section and is flared away 40 from the member 1, and the lower part of the member 1 is mounted by a spring-steel yoke 6 that rests against the post so as to be expanded by the latter's flared shape when forced towards it.

45 50 The second example is further distinguished in that the metal strips 2 have their top edges bent backwardly, as at 2^a.

The member 1 in this second example functions in the same manner as it does in the first example, so far as maintenance of strip tensions is

concerned. However, it also functions to mount the strips in a vertical plane in such a manner that a colliding vehicle can force the strips from a vertical plane so that they assume a downwardly angling position which tends to wedge the vehicle beneath it. It is for this purpose that the backward angling portions 2^a are provided, since otherwise excessive damage to the vehicle might result from the cutting action of the sharp-edged strips. The angular position of the strips is possible because the spring bar 4 is sufficiently elastic to act as a hinging mount, while the elasticity of the yoke tends to resist swinging motion of the member 1 by wedging action on the flared post 5.

15 We claim:

1. A guard rail including a flat spring metal member that is looped at both sides of its center so as to bring its end portions together and which has its ends cut and formed to provide interfitting 20 and mutually registering elongated loops, flat metal strips having adjacently abutting ends fixed to said end portions and urged together by the elasticity of said member and a pin arranged through said elongated loops.

2. A guard rail including a flat spring metal member that is looped at both sides of its center so as to bring its end portions together and which has its ends cut and formed to provide interfitting and mutually registering elongated loops, 30 flat metal strips having adjacently abutting ends fixed to said end portions and urged together by the elasticity of said member, a post and a spring metal bar mounting said member in an upright position by its upper part so that its lower part 35 may swing toward said post.

3. A guard rail including a flat spring metal member that is looped at both sides of its center so as to bring its end portions together and which has its ends cut and formed to provide interfitting and mutually registering elongated loops, flat metal strips having adjacently abutting ends fixed to said end portions and urged together by the elasticity of said member, a post 40 and a spring metal bar mounting said member in an upright position by its upper part so that its lower part may swing towards said post, the latter being flared away from said member and the lower part of said member being mounted by 45 a yoke that rests against said post so as to be expanded by the latter's flared shape when forced theretowards.
